RAZOR RACK

Sheila S. Wilkins, 3018 Merrell Road,
Dallas, Tex. 75229

Filed Jan. 21, 1972, Ser. No. 219,925

Term of patent 14 years

Int. Cl. D6—06

U.S. Cl. D6—88

FIG. 1

FIG. 2

FIG. 3

FIG. 4

FIG. 5

FIG. 1 is a front perspective view of a razor rack showing my new design;

FIG. 2 is a front elevational view thereof;

FIG. 3 is a top plan view thereof;

FIG. 4 is a bottom plan view thereof; and

FIG. 5 is a side elevational view thereof.

The side of the razor rack not shown is substantially the same in appearance as the side shown.

I claim:

The ornamental design for a razor rack, substantially as shown and described.
